UNITED STATES PATENT OFFICE.

EUSTICE E. DICKERSON, OF CLEBURNE, TEXAS.

SUCTION-FAN OR BLOWER.

1,147,078.

Specification of Letters Patent.

Patented July 20, 1915.

Application filed January 23, 1915. Serial No. 4,007.

To all whom it may concern:

Be it known that I, EUSTICE E. DICKERSON, citizen of the United States, residing at Cleburne, in the county of Johnson and State of Texas, have invented certain new and useful Improvements in Suction Fans or Blowers, of which the following is a specification.

My invention has relation to a combined 10 suction fan or blower adapted particularly for use in the conveying and cleaning of fibrous materials such for instance as cotton or the like and in such connection it relates more particularly to the arrangement and 15 construction of such a fan and blower.

In the conveying, cleaning and distributing of raw fibrous material such as cotton and the like, an essential feature of the apparatus is a blower and suction fan interposed in the system or apparatus at a point 20 between the source from which the fiber is taken to the first cleaning mechanism of the apparatus. In an apparatus such as is disclosed in my companion application for patent filed of even date herewith appropriate 25 means are shown, described and claimed whereby after the cotton or fiber is sucked from the source of supply it is forced under pressure of air to the subsequent means and 30 instrumentalities through which the fiber must pass to be cleaned and otherwise prepared prior to its distribution, still under pressure of air, to the gins or other machines for subsequent treatment of the fiber.

It is the object of my present invention to 35 provide a suction fan or blower the parts of which are so constructed and arranged that during the passage of the fibrous material through the fan and blower the material 40 will be partly cleansed before it leaves the fan or blower under pressure of air to enter the respective cleaning mechanisms in the aforesaid or similar apparatus.

To this end my invention consists, first, 45 in providing a combined suction and blowing apparatus wherein the fan proper carries at its inlet face a perforated plate secured to and revolving with the blades of the fan, second, in providing a substantially 50 cylindrical chamber having both its peripheral wall and its side wall perforated, within which chamber the fan is adapted to revolve, said chamber communicating at its periphery with the outlet from the blower 55 and at its side wall with an inlet from the suction pipe; third, in providing an inlet

from the suction pipe to the perforated side wall of the fan chamber, said inlet having an outwardly flaring perforated flange at the point of its connection with the suction pipe and thereafter the body of the inlet pipe tapering to a smaller diameter to a point where it connects with the flat perforated wall of the fan chamber the tubular wall of said body of the inlet pipe being also 60 perforated; and fourth, in providing an outer shell or casing inclosing the perforated inlet pipe, the perforated fan chamber and the fan with perforated side wall, said casing having a cylindric fan chamber, an inlet 65 chamber and a discharge chamber.

The nature and scope of my invention will be more fully understood from the following description taken in connection with the accompanying drawings forming part hereof, 75 in which,

Figure 1 is a side elevational view of a combined suction fan and blower embodying main features of my invention. Fig. 2 is an end elevational view of the 80 same. Fig. 3 is a cross sectional view taken on the line *a—a* of Fig. 1. Fig. 4 is a longitudinal sectional view taken on line *b—b* of Fig. 3, and Fig. 5 is a cross sectional view taken on line *c—c*, of Fig. 1, and illustrating 85 the connection between the discharge chamber of the fan and the discharge pipe.

Referring to the drawings the shell or casing for the fan and blower mechanism consists essentially of three parts, namely a 90 main cylindrical body 1 wherein the fan is adapted to rotate; a frusto-conical leg or arm 2 projecting from the side of the body to the inlet or suction pipe 3, the taper of the leg or arm 2 being from the side of cylindric body 1 to the pipe 3; and third a discharge chamber 4 of preferably rectangular cross section and projecting tangentially from the rim of the cylindric body 1 and tapering into a tube or pipe 5 which is the 100 discharge pipe of the apparatus to which air under pressure is delivered by the fan 6. The blades 7 of the fan radiate from a sleeve 8 keyed or otherwise secured to a shaft 9 extending outside the casing of body 1. The 105 shaft 9 has its bearings 10 in a frame or standard 11 and this standard or frame 11 serves as a support for the annulus or collar 12 bolted or otherwise secured to one side wall 1^a of the main body 1 of the blower casing. This side wall 1^a is solid except for an aperture through which the bearing 10 pro-

jects to support the shaft 9 within said body 1. The opposite side of the main body 1 is entirely open at the point of junction of the body 1 with the base of frusto-conical leg or arm 2, as clearly indicated in Fig. 3.

The peripheral wall of body 1 is not continuous but is bent tangentially as at 1^b to form a rectangular or square duct 13 leading to the discharge chamber 4 as clearly shown in Fig. 4.

The main body 1 has an interior lining 14 of perforated sheet metal separated some distance from the peripheral wall of said body and concentric therewith. The fan 6 revolves in the concentric perforated compartment thus formed. The face 15 of fan 6 which is adjacent to the inlet or suction chamber 2 is in the form of a perforated disk or plate suitably united to and carried by the edges of the fan blades 7. The opposite face 16 of fan 6 is in the form of an annulus or ring which is not perforated and revolves adjacent to the closed side wall 1^a of the body 1. The perforated compartment 14 has its side adjacent to the suction chamber 2 partly inclosed by an annulus or ring 17 of perforated sheet metal and to the central opening of this ring 17 is bolted or otherwise secured the smaller end of a perforated nozzle 18 traversing or crossing through the suction chamber 2 and extending from plate or ring 17 to the suction pipe 3. At the point of connection with said pipe 3, the nozzle 18 flares outwardly into an annular perforated collar or flange 19 as clearly shown in Fig. 3.

The frusto-conical shell forming the wall of the suction chamber 2 is bolted or riveted to the side of main body 1 and said side and shell for chamber 2 are suitably supported in a frame or standard 20, the two standards 11 and 20 thus constituting the support for the fan and blower. The space 21 between the perforated compartment 14 and the outer shell for body 1 communicates preferably at the base of the fan with a pipe 22 leading to the exterior of the fan and blower. The space 23 between the perforated nozzle 18 and the wall of the conical leg or arm 2 also communicates with the space 21 through the perforated flange 24 projecting peripherally from the perforated compartment 14 beyond the perforated annulus or ring 17 forming a partially side closure for said compartment 14.

In the operation of the device, the fan blades 7 in revolving within the perforated compartment 14 suck air and fibrous ma-

terial through pipe 3 and perforated nozzle 18 into the compartment 14. The fibrous material is prevented from reaching the fan blades 7 by the perforated disk 15 carried by said blades. In its passage through nozzle 18 the fiber is relieved of some of its dirt or dust which passes through the perforations 65 of the nozzle 18 into the compartment 23 in leg 2 in which a partial vacuum is created by the revolution of the fan. The fibrous material under air pressure is then forced through compartment 14 to the outlet compartment 4 and thence under air pressure into the distributor or discharge pipe 5. In its passage through compartment 14 loose dirt, etc., is blown from the fiber through the perforations in the peripheral wall of said 75 compartment 14 to the space 21 between said wall and the interior of the shell for the body 1 of the casing.

Having thus described the nature and objects of my invention, what I claim as new 80 and desire to secure by Letters Patent is,

1. In a combined fan and blower, a casing arranged with a side conical leg forming an inlet or suction chamber, a main cylindrical body wherein the fan is arranged to rotate, 85 and an outlet leading from the main body tangentially to the periphery of said main body, of a screen partition located within and concentric with the peripheral wall of the main body of the casing, a fan revolving 90 in the compartment formed by said screened partition, an annulus of perforated metal forming an end closure for a portion of said screened compartment, the central opening in said annulus communicating with the inlet to the suction chamber, and a perforated disk forming that face of the fan which revolves adjacent to the inlet opening in said annulus.

2. In a combined fan and blower provided 100 with an inlet suction chamber, an outlet discharge chamber and an intermediate chamber wherein the fan is arranged to rotate, of a screened compartment formed in the intermediate chamber and a perforated nozzle 105 connecting said screened compartment with the inlet to the suction chamber, said nozzle traversing said suction chamber of the casing.

In testimony whereof I have signed my 110 name to this specification in the presence of two subscribing witnesses.

EUSTICE E. DICKERSON.
